Des. 214,929
Patented Aug. 12, 1969

214,929

TOY CAMERA

Ralph W. Crawford, East Aurora, N.Y., assignor to
Fisher-Price Toys Inc., East Aurora, N.Y., a corpora-
tion of New York

Filed Mar. 4, 1968, Ser. No. 10,831

Term of patent 14 years

Int. Cl. D21—02; D16—01

U.S. Cl. D34—15

FIG. 1 is a front perspective view of a toy camera showing my new design with the dotted line portion showing a conventional wrist strap;

FIG. 2 is a rear portion view thereof; and

FIG. 3 is a side elevation thereof as viewed from the left in FIG. 1 with the dotted line portion showing a conventional wrist strap.

I claim:

The ornamental design for a toy camera, substantially as shown and described.
